CHICKEN COOP

Eugene W. Aylor, Brightwood, Va.

Application June 19, 1952, Serial No. 294,340

5 Claims. (Cl. 20—16)

1

The present invention relates in general to chicken coops, and more particularly to the type of coops used for transportation of poultry, having resiliently latched doors incorporated therein.

It is conventional practice in storing coops in transportation vehicles for delivery to market of piling such coops in tiers of considerable height. In stacking and removing coops from the upper rows of such tiers, the attendants usually stand on one or several of such coops. By reason of the rough handling to which these coops are subjected during such stacking, they must be extremely rigid in construction and able to withstand the strains and shocks to which they are habitually subjected.

According to conventional construction practice, coops of this type are usually formed in a rectangular shape with the side and top walls formed by spaced dowels, so that a maximum quantity of air is admitted to the poultry, and at the same time substantial strength is provided in the construction to resist the downward force of a large number of such coops piled one upon the other.

For convenience in filling and emptying the coops, a pivoted door is usually provided in the top of the coop, which is resiliently biased to latched condition, usually by means of a coil spring surrounding a pivot-forming dowel extending through one end of the door, the coil spring serving to bias the door toward one side of the door opening and into latching engagement with a latching pin projecting from that side of the door opening. An important feature of such hinged doors for chicken coops, however, is that the door when opened by the attendant will remain in open position and may be readily closed and automatically latched by merely brushing the door either with the elbow or with the poultry being carried. Such latching arrangement, however, must be efficient and positive in operation to prevent escape of other chickens from the coop. Also, failure to securely close the hinged door exposes the coop to almost certain injury in the course of shipment.

An object of the present invention, therefore, is the provision of a poultry coop of the type referred to in which an improved door construction insures the automatic complete closure of the door on slight movement of the door from open position.

Another object of the present invention is the provision of a novel poultry coop of the type having a hinged door incorporated therein, which

2

door is provided with a resilient latching mechanism of improved construction.

Another object of the present invention is the provision of a novel chicken coop of the type having a hinged door with a resilient latching mechanism for positively latching the door in closed position, which coop is of simple and durable construction.

Other objects, advantages and capabilities of the present invention will become apparent from the following detail description taken in conjunction with the accompanying drawings, wherein only a preferred embodiment of the invention is illustrated.

15 In the drawings:

Figure 1 is a top plan of a chicken coop embodying the present invention;

Figure 2 is a vertical longitudinal section of the medial portion of the chicken coop to illustrate the novel door construction incorporated therein, taken along the lines 2—2 of Figure 1;

Figure 3 is a top plan view of the portion of the chicken coop forming the door latching arrangement illustrating the position assumed by the parts during unlatching movement thereof;

Figure 4 is a vertical transverse section, taken along the lines 4—4 of Figure 3.

In the drawing, wherein like reference characters designate corresponding parts throughout the several figures, the numeral 10 designates generally a rectangular frame forming the top of a shipping crate or coop for poultry, having longitudinal side frame members 11 and transverse end frame members 12. The connection between the adjacent ends of the side and end frame members 11 and 12 may be a mortise and tenon connection of conventional construction, or the side frame members 11 may be laid on top of the end frame members 12, in each instance the frame members being preferably bolted to each other.

As is the conventional practice, a plurality of parallel dowel members 13 extend between the frame members forming the top and sides of the coop to constitute the closure for the walls thereof, the ends of the dowel members forming the top of the coop being secured in the frame members 11, preferably by providing spaced holes in the frame members into which the ends of the dowel members are inserted and secured.

A pair of longitudinally extending cross frame members are also illustrated, consisting of the uninterrupted cross frame member 14 and the components 15 and 16 forming an interrupted

cross frame member parallel to the frame member 14 and interrupted to provide the door opening 17.

Preferably, transverse supporting straps 18 are bolted to the side frame members 11 intermediate the length thereof and extend transversely therebetween to define, together with one of the frame members 11 and the cross frame member 14, the limits of the door opening 17.

The hinged door, generally indicated by the reference character 19, is formed in a generally conventional manner of a pair of side frame members 20 and 21, each having facing recesses in the inwardly disposed face thereof accommodating a series of parallel dowels 22. As illustrated in the drawing, one end of each of the two side frame members 20 and 21 is provided with a hole extending therethrough and surrounding one of the dowels 23 forming the top closure of the coop and defining the pivot rod 20 for the door 19.

The outermost dowel 24 at the other end of the door 19 is securely seated at one end in one of the side frame members of the door, for example, the frame member 20, and is loosely accommodated in a guide slot 25 formed in the other door frame member 21 to permit the dowel member 24 to be forced inwardly against its own internal resiliency and inserted or withdrawn from the keeper recess 26 in the frame member 16 for latching and unlatching the door. As shown in Figures 2 and 4, the guide slot 25 extends at an angle inclined upwardly and away from the adjacent portion of the door opening so that the latching dowel 24 is normally seated by its own internal resilient bias when the door 19 is in closed position. The projecting end of the cross frame member 16 is beveled away from the door opening as indicated at 27 to cam the latching dowel 24 inwardly when the door 19 is pivoted downwardly into contact therewith.

As illustrated in Figure 2, the door frame members 20 and 21 are so arranged relative to the transverse supporting straps 18 that the frame members rest upon both supporting straps when in closed position.

Operation of the hinged door of the chicken coop is as follows: Assuming the door to be in closed position, the latching dowel 24 is grasped by the hand of the attendant and drawn toward the remaining dowels 22 forming the door 19 to unseat the latching dowel 24 from the latching recess 26 and permit the door 19 to be pivoted into an erect open position. If the door is fully opened, the door will pivot past center into a position where the door frame members 20 and 21 contact the dowel member 13 adjacent the door opening 17 and remain at rest in this position. After the attendant has grasped hold of a number of chickens and lifted them out of the coop, he need only swing the door past the vertical axis extending through the pivot forming dowel 23, either by engaging the door with his elbow or with the handful of chickens, and the momentum of the door will carry it downwardly to bring the latching dowel 24 into engagement with the beveled surface 27 of the frame member 16 and cam the latch rearwardly as the door descends to the position where the resiliency of the latching dowel 24 biases it into seating position within the latching recess 26.

The inward camming of the latching dowel 24 is assisted by the angular inclination of the guide slot 25, as the free end of the latching dowel 24

is forced upwardly into contact with the upper surface of the slot 25 on engagement with the beveled surface 27. The upward inclination of the upper surface of the slot 25 translates the upward force on the end of the latching dowel 24 into an inwardly directed component assisting movement of the dowel 24 inwardly past the upper edge of the latching recess 26.

This same angular inclination of the guide slot 25 likewise assists in maintaining the door latched when in closed position, as the free end of the dowel 24 is forced downwardly into contact with the lower surface of the guide slot 25 when an opening force is directed against the door. This downwardly and outwardly inclined lower surface of the guide slot 25 resolves the downward force into a component directed toward the latching recess 26, thus insuring intimate seating of the latching dowel 24 within the latching recess 26 under such conditions.

It will be apparent from the foregoing description that a novel hinged door construction for chicken coops has been provided, which may be easily and readily manipulated by the attendant in opening and closing the same, which automatically latches the door on pivoting of the door into closed position under force of gravity, and which securely maintains the door in latched condition unless manually unlatched by the attendant.

Various modifications may be made in the invention without departing from the spirit and scope thereof, and it is desired, therefore, that only such limitations be placed thereon as are imposed by the prior art and set forth in the appended claims.

What is claimed is:

1. In a chicken coop having a door opening and a door pivotally supported therein for rotation about an axis in the plane of an adjacent one end of said opening, latching means for said door comprising a catch member on said coop projecting into said door opening adjacent the free end of said door and having a latching recess therein facing inwardly of said door opening, an elongated latching element disposed transversely across said door at the free end thereof, means resiliently biasing said latching element laterally in the plane of said door relative to one end thereof into seated condition in said latching recess, and guide means on said door having cam surfaces inclined to the plane of said door to engage said latching element and translate upward and downward forces thereon into movement on said latching element away from and toward said recess respectively.

2. In a chicken coop, having a door opening therein, a door, and means pivotally supporting said door in said door opening for rotation relative to a transverse axis adjacent one end of said door opening, a fixed keeper member projecting into said door opening opposite said pivotal supporting means, said keeper member having a keeper recess therein facing inwardly of said door opening, an elongated movable latching element having at least one end fixed in said door and disposed in the plane of said door adjacent one end thereof for engagement with said fixed keeper member, said latching element being resiliently biased in the direction of said keeper recess and deformable out of engagement therewith, and said door having a guide slot therein inclined to the plane of said door and receiving said movable latching element for camming said latching element away from and to-

ward said keeper recess in response to upward and downward forces exerted by said fixed keeper member on said latching element respectively.

3. In a chicken coop having a door opening and a door pivotally supported therein on an axis lying at one end of said opening and having spaced side frame members, a latching mechanism for said door comprising a fixed keeper member projecting into said opening having a latching recess in an end thereof facing inwardly of said door opening opposite said one end thereof, a latching rod extending between said door frame members at the ends thereof adjacent said keeper member and having one end anchored in one of said door frame members, said latching rod being resiliently biased toward said recess, the other of said door frame members having a guide slot accommodating the other end of said latching rod and having cam surfaces inclined to the plane of said door for camming said latching rod away from said latching recess on upward forces thereon and urging said latching rod toward said latching recess on downward forces thereon.

4. In a chicken coop having a door opening formed in the top thereof, a door having spaced side frame members, a plurality of spaced parallel dowels extending between said door frame members, one of said dowels extending through said side frame members adjacent one end of said door and forming pivotal supporting means for said door, a fixed catch member having a latching recess in an end thereof projecting into said door opening opposite said pivot-forming dowel, another of said dowels forming a latching member extending between said door frame members at the end thereof opposite said pivot-forming dowel and having one end anchored in one of said door frame members, said latching dowel being deformable laterally in the plane of said door and resiliently biased toward said recess, the other of said door frame members having a guide slot inclined to the plane of said door and accommodating the other end of said latching dowel, the upper and lower side walls of said

slot forming cam means for urging said latching dowel away from said latching recess on upward forces thereon and urging said latching dowel toward said latching recess on downward forces thereon.

5. In a chicken coop having a door opening formed in the top thereof, a door having spaced side frame members, a plurality of spaced parallel dowels extending between said door frame members, one of said dowels extending through said side frame members adjacent one end of said door and forming pivotal supporting means for said door, a fixed catch member having a latching recess in an end thereof projecting into said door opening opposite said pivot-forming dowel, another of said dowels forming a latching member extending between said door frame members at the end thereof opposite said pivot-forming dowel and having one end anchored in one of said door frame members, said latching dowel being deformable laterally in the plane of said door and resiliently biased toward said recess, the other of said door frame members having a guide slot for accommodating the other end of said latching dowel, said guide slot having upper and lower side walls inclined to the plane of said door and forming cam means to be engaged by said latching dowel and translate upward and downward pressure exerted by said catch member into movement of said latching dowel in the plane of said door away from and toward said latching recess respectively, and an inclined surface on the projecting end of said fixed catch member to be engaged by said latching dowel on downward movement of said door and cam the latching dowel beyond said projecting end.
